G. B. KEPLINGER

SIREN SQUAWKER

Filed Dec. 10, 1927

UNITED STATES PATENT OFFICE.

GEORGE B. KEPLINGER, OF CHICAGO, ILLINOIS.

SIREN SQUAWKER.

Application filed December 10, 1927. Serial No. 239,049.

My invention is concerned with what I call a siren squawker, and is an exceedingly simple construction which can be cheaply manufactured, and which can be used to produce a musical note or sound that can be varied in pitch, by blowing feebly into it, so that it can be operated by a baby or a very small child.

To illustrate my invention, I annex hereto a sheet of drawings, in which the same reference characters are used to designate identical parts in all the figures, of which,—

Fig. 1 is a perspective view of the device;

Fig. 2 is a plan view in central, horizontal section;

Fig. 3 is a plan view of the supporting wire detached;

Fig. 4 is a perspective view of the mouthpiece; and

Fig. 5 is a perspective view of the rubber before the same has been attached.

In carrying out my invention in its preferred form, I employ a tubular mouthpiece 10, which is conveniently made of wood and has one end 11 shaped to fit the lips, and the other end provided with an annular channel or groove 12 to receive the thickened end 13 of the rubber 14. A pair of flanges 15 and 16 may be employed, leaving a cylindrical space between them around which may be pasted or otherwise secured the paper or celluloid strip 17 carrying any desired legend or advertising matter.

The supporting member preferably consists of a piece of wire having the central loop portion 18, which is of the proper size to spring into and be securely held in the end of the tube of the mouthpiece, as will be readily apparent in Fig. 2. On either side of the central portion are the arms 19, which preferably have the humped portion 20 and terminate in the short closed loops 21, so that when the rubber tube is stretched over the same with the thickened end 13 fitting in the channel 12, most of the body of the tube will be stretched over the wire tightly enough so that when air is blown through the tube a musical tone will be produced. The pitch of this tone can be raised by blowing harder or by cutting off a portion of the vibrating surface by grasping a portion of the vibrating outer end adjacent one or both sides between the thumb and finger.

While I have shown and described my invention as embodied in the form which I a-

present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In a device of the class described, the combination with a tubular mouthpiece having a supporting member on the outer end thereof, of a piece of elastic flexible material stretched on said supporting member so as to produce a plane surface under tension extending in the direction of the air blown through the mouthpiece and beyond it.

2. In a device of the class described, the combination with a tubular mouthpiece having a supporting member on the outer end thereof, of a piece of elastic flexible material stretched on said supporting member so as to produce a pair of parallel, slightly separated plane surfaces under tension extending in the direction of the air blown through the mouthpiece and beyond it.

3. In a device of the class described, the combination with a tubular mouthpiece, or a short tube of elastic flexible material, and a supporting member carried by the mouthpiece and adapted to stretch the tube beyond the mouthpiece so that air blown through the mouthpiece will vibrate the stretched portion of the tube.

4. In a device of the class described, the combination with a tubular mouthpiece, of a short tube of elastic flexible material adapted to fit over the outer end of the mouthpiece, and a supporting member carried by the mouthpiece and adapted to stretch the outer end of the tube beyond the mouthpiece so that air blown through the mouthpiece will vibrate the stretched portion of the tube.

5. In a device of the class described, the combination with a tubular mouthpiece, of a short rubber tube, and a supporting member carried by the mouthpiece and adapted to stretch the tube beyond the mouthpiece so that air blown through the mouthpiece will vibrate the stretched portion of the tube.

6. In a device of the class described, the combination with a tubular mouthpiece, of a short tube of elastic flexible material, and a supporting member comprising a stem portion adapted to fit in the outer end of the

- tubular mouthpiece, and a wider body portion over which the elastic tube is stretched beyond the mouthpiece, substantially as shown and described.
7. In a device of the class described, the combination with a tubular mouthpiece, of a short tube of elastic flexible material, and a wire supporting member comprising a central stem or loop portion adapted to fit in the outer end of the tubular mouthpiece and two or more widely separated arms over which the tube of elastic material is adapted to be stretched beyond the mouthpiece.
8. In a device of the class described, the combination with a tubular mouthpiece, of a short tube of elastic flexible material, and a wire supporting member comprising a central stem or loop portion adapted to fit in the outer end of the tubular mouthpiece and a pair of widely separated arms over which the tube of elastic material is adapted to be stretched beyond the mouthpiece, said arms having their ends furnished with short closed loops.
9. In a device of the class described, the combination with a tubular mouthpiece having an annular groove near its outer end, of a short tube of elastic flexible material having one end thickened and adapted to fit tightly in said annular groove, and a supporting member carried by the mouthpiece and adapted to stretch the other end of the tube so that air blown through the mouthpiece will vibrate the same.
10. In a device of the class described, the combination with a tubular mouthpiece having an annular groove near its outer end, of a short tube of elastic flexible material having one end thickened and adapted to fit tightly in said annular groove, and a supporting member carried by the mouthpiece and adapted to stretch the other end of the tube so that air blown through the mouthpiece will vibrate the same, said supporting member comprising a stem portion adapted to fit in the outer end of the tubular mouthpiece and a wider body portion.
11. In a device of the class described, the combination with a tubular mouthpiece having an annular groove near its outer end, of a short tube of elastic flexible material having one end thickened and adapted to fit tightly in said annular groove, and a supporting member carried by the mouthpiece and adapted to stretch the other end of the tube so that air blown through the mouthpiece will vibrate the same, said supporting member comprising a wire having a central stem or loop portion adapted to fit in the outer end of the tubular mouthpiece and a pair of widely separated arms over which the tube is stretched.
12. In a device of the class described, the combination with a tubular mouthpiece having a rounded outer end to fit between the lips, an annular groove near its other end, and a plane cylindrical surface between the outer end and the groove, of a short tube of elastic flexible material having a thickened inner end adapted to fit tightly in the annular groove, and a supporting member carried by the mouthpiece and adapted to stretch the tube so that air blown through the mouthpiece will vibrate the stretched portion thereof.

In witness whereof, I have hereunto set my hand this 6th day of December, 1927.

GEORGE B. KEPLINGER.
